United States Patent Office.

BENONI F. PARTRIDGE, OF SYRACUSE, NEW YORK.

Letters Patent No. 64,137, dated April 23, 1867.

IMPROVED QUILTING-FRAME.

The Schedule referred to in these Letters Patent and making part of the same.

TO ALL WHOM IT MAY CONCERN:

Be it known that I, BENONI F. PARTRIDGE, of the city of Syracuse, in the county of Onondaga, and State of New York, have invented a new and useful improvement for an Adjustable Quilting-Frame; and I do hereby declare that the following is a full, clear, and exact description of the construction and operation of the same, reference being had to the annexed drawings, making a part of this specification, in which—

Figure 1 is a perspective view.

Like letters refer to like parts.

Letter A represents the axis; letters B B the rollers; letters C C the extension-bars; letters D D the legs; letters *a a a* the set-screws; letters *b b b* the guides; letters *c c* the stay-rods; letters *d d* the slot in the extension-bars. The axis, the rollers, the extension-bars, and the legs are made of wood or any metallic substance. The rollers are round or can be made octagonal. The extension-bars are fastened to each end of the rollers by set-screws; and fastened to the extension-bars by guides are the legs. In the lower end of each extension-bar is a slot, so as to permit the quilting-frame to be expanded or contracted in size at the option of the operator. The axis is a bar extending through the centre of the quilting-frame, and the ends of which are fastened to the legs by set-screws. The guides are to hold the extension-bars to their proper and desired place. The stay-rods are to hold the frame in the desired position while fastening the quilt on to the frame, as then the set-screws are all loosened; and when the quilt is fastened on the frame and extended to its full length, then the frame is fastened to its position by the set-screws. The quilt is rolled up to suit the operator by loosening the set-screws on the ends of the rollers and turning the rollers.

What I claim as my invention, and desire to secure by Letters Patent, is—

The combination and arrangement of the axis, the rollers, the extension-bars, the legs, the set-screws, the guides, the stay-rods, the slot in the extension-bars, all constructed and operating substantially as and for the purpose shown and described.

BENONI F. PARTRIDGE.
